[57] CLAIM

The ornamental design for a collar fitting for a fixture, as shown and described.

DESCRIPTION

FIG. 1 is a perspective view of a collar fitting for a fixture according to the present invention, the elements of the fixture as well as the bottom border of the collar fitting being shown in broken lines and thus not forming a part of the claimed design;

FIG. 2 is a top plan view thereof;

FIG. 3 is a right side elevational view thereof;

FIG. 4 is a left side elevational view thereof;

FIG. 5 is a front elevational view thereof; and,

FIG. 6 is a rear elevational view thereof.
